BENJAMIN J. COHON, OF BAYONNE, AND LOUIS MOSKOWITZ, OF WESTWOOD, NEW JERSEY.

LOCK.

1,186,171.

Specification of Letters Patent.

Patented June 6, 1916.

Application filed January 27, 1916. Serial No. 74,631.

To all whom it may concern:

Be it known that we, BENJAMIN J. COHON and LOUIS MOSKOWITZ, citizens of the United States, and residents of Bayonne, in the 5 county of Hudson and State of New Jersey, and Westwood, in the county of Bergen and State of New Jersey, respectively, have invented certain new and useful Improvements in Locks, of which the following is a 10 specification.

We have invented an improved lock having for its object to provide a construction by which a door or the like can be secured in a way that will entirely obviate all possibility 15 of the lock being successfully manipulated by unauthorized persons seeking an entrance. This and other objects and advantages of our invention will appear from the following description, taken in connection 20 with the accompanying drawings; and be precisely pointed out in the appended claims. But the disclosure herein is illustrative only and the principle of our invention may be embodied in devices other than the one 25 shown; as indicated by differences in the modes by which the characteristics of our improvement, as stated in the several claims, are expressed.

On the drawings: Figure 1 is a front view 30 of a lock made according to our invention as it will look when opened; Fig. 2 is a similar view showing the parts in operative position; Fig. 3 is a section on line 3—3 of Fig. 2; and Fig. 4 is a view of a detail.

35 The same numerals of reference indicate the same parts throughout.

We show at 1 a support or casing for the mechanism of the lock; and through the side of the casing projects an operating element, 40 such as a main shaft 2, mounted in a bearing 3. This bearing is fixed to the casing, and extends out from one side of the casing over the whole length of the exterior part of the shaft to the usual knob 4 thereon; whereby 45 it covers and protects the outside of the shaft, so that by the knob alone, except when the proper key is used, can the lock be unfastened. The importance of this feature will be explained at length hereinafter.

50 Inside the casing are two elements preferably in the shape of rectangular frames 5 and 6, having relatively large central openings, the former acting as a carrier for the latter. This carrier is supported by suitable

devices such as lugs 7 on the inside of the 55 casing and is mounted so as to be capable of reciprocation by a revoluble means, such as a cam 8 on the shaft 2, received in the central opening of the carrier. This cam is designed to engage opposite inner edges of 60 the carrier and impart to it a movement of translation toward and from an opening 9 in the end of the casing 1. The other frame 6 is provided with projections 10 entering slots 11 in the carrier 5, extending transversely of its line of movement. Hence the frame 6, while movable in unison with the carrier 5 is also movable with respect thereto. To effect movement of the frame 6 translationally across the carrier we employ 70 revoluble means, such as a second cam 12 on the shaft and mounted to engage opposite inner edges of the frame 6. This cam 12 is spaced angularly from the cam 8 and the edges engaged by the cam 12 will be transverse with respect to the edges engaged by 75 the cam 8. That is, if the cam 8 contacts with vertical inner edges of the carrier 5, the cam 12 will contact with the opposite horizontal inner edges of the frame 6, and whereas the carrier will be moved back and forth when the casing is in position upon a door or window the frame 6 will move up 80 and down on the carrier 5.

The frame 6 will bear a locking projection 85 13, about as wide as the length of the opening 9 and extending beyond the lower edge of the frame 6. This projection 13 is adapted to pass freely through the opening 9, and engage with a similar opening 14 in a plate 90 15 on the jamb 16 of the door frame. The frame 6 and its projection thus constitute a latch bolt, and this latch bolt with its projection will always extend beyond the forward end of the carrier 5.

In practice the casing 1 with the mechanism it bears will be fixed to a door 17, indicated by broken lines in Figs. 1 and 2, and the casing will be either on the side of the door, as shown, or in a pocket or recess of 100 the door; and when the projection 13 is withdrawn, the carrier 5 with the frame 6 will be as far back, and the frame 6 as far up on the carrier, as they will go. Under these circumstances the projection 13 will 105 have its advanced edge in the opening 9, and will about fill the same. When the door is closed, the casing 1 will be in line with the

plate 15 and openings 9 and 14 will register. Hence by turning the knob 4 the frames 5 and 6 will first be operated in unison to move the projection 13 through the opening 5 9 into position to project from the casing and enter the opening 14 till it clears the lower edge of the latter. Up to this point the cam 8 alone takes effect. Then the cam 12 engages the frame 6, depressing it and 10 dropping the projection 13 behind the lower edge of the opening in the plate 15, and it will be seen that only the latch bolt sticks out of the casing; while the carrier 5 is always inside. The door is now fastened 15 securely.

We also provide a round opening 18 in the inner end of the shaft 2, to receive the operating shank of any suitable mechanism, indicated at 19 in Fig. 3, adapted to be 20 turned by a key, to revolve the shaft 2 by means of elements described below. This mechanism 19 may be an ordinary tumbler construction and it will be secured to the door on the side which is presented to the 25 exterior of the building, room or apartment which is to be closed. Our improved lock will be on the opposite or inner side. Hence the door can be opened by a key from without or by the knob from within.

30 The merit of our construction resides in the fact that the lock cannot be picked or the door worked by prying a tool between the casing 1 and the plate 14. It will be apparent from the foregoing that the projection 13 will hold the door shut as soon as it enters the plate 15 and when it drops behind the lower edge of the opening 14, the disengagement of the projection, except by using the knob or a key is impossible, unless 35 sufficient force to shatter the door or casing is exerted. Further, the bearing 3 will prevent the withdrawal of the projection 13 by any one boring through the door beside the casing, and trying to engage the shaft mechanically to turn it; as this bearing covers 40 and protects the shaft and renders such a proceeding entirely futile.

If desired, the side of the casing opposite that carrying the bearing 3, may be made 50 removable, to afford access to the mechanism when the casing is detached from the door. We also employ a spring 20, engaged by a stud 21 in the casing to press on the inner end of the shaft and maintain the projection 13 positively in either operative or inoperative position. A cross arm 22 on the shaft, having curved ends, will facilitate such a result by engaging the outer end of the spring 20. When the parts are as shown 55 in Fig. 1, the spring presses on the cross arm throughout its length, as it is then horizontal, and prevents any movement of the parts that might be caused by jarring, vibration, etc., of the door or building. Also, when 60 the parts are as shown in Fig. 2, with the

latch bolt fully shot the shaft will have been turned through half a circle, and the spring will again press down over the whole length of the arm 22. For the intermediate position, the arm 22 will be vertical, and one 70 of the rounded ends of the same will be received in a rounded recess produced by bending the spring. Hence the spring will hold the projection 13 when it is partly shot after it enters the opening 14, but before it is 75 dropped behind the lower edge thereof; or after it is raised to clear the lower edge of the opening 14, but before complete withdrawal.

From the above description it will be appreciated that the mechanism of our lock enables us to move the locking element positively both when it is caused to project from the casing and depressed to get the projection 13 behind the striker plate; and when 80 it is withdrawn from the striker plate and back into the casing. We also get the holding effect of the cams 8 and 12, acting as above stated to "dog" the carrier and latch bolt when the latter is fully shot, and prevent the complete or partial withdrawal of the bolt except by turning back the shaft 2 by the knob or key. It is, of course, to be understood that our lock may be used, not only on doors, but also on windows and in 90 fact on any kind of construction by which an opening is to be closed up securely.

By inspecting Fig. 2 closely the observer will see that the position of the cam 12, when the projection 13 is moved through the openings 9 and 14 and dropped, is such that the frame 6 with the projection 13 cannot be raised so as to make the projection clear the lower edge of the opening 14 by any degree of force whatever. This is because the 100 lowest point of the cam in contact with an inner edge of the frame 6 is directly below the axis of the shaft 2, and any upward push on the frame will be from this point toward the center of the shaft, which will afford no 105 turning couple; and movement of the frame and rotation of the shaft by means of a tool from below simply cannot be obtained. At the same time the cam 8 abuts squarely 110 against the forward inner edge of the carrier 5, and any force applied to bring about the rearward movement of the carrier by an instrument from without will necessarily be exerted from the point of contact from the cam 8 and carrier 5 directly through the 115 shaft 2. Consequently the carrier and the latch bolt cannot be pushed back by a tool, any more than the frame 6 can be pushed up. Our lock then can only be unfastened by the intermediation of the shaft 2, 120 reversely actuating the cams. It will also be seen that the knob 4 has no boss or projection on the face it presents to the casing 1; but on the contrary this face is as flat as 125 possible. The knob is of course rigid with 130

the shaft, as by making it integral therewith, or by giving it a recess which enables it to be fitted on and secured to the end of the shaft 2. Hence the bearing 3 can extend 5 out from the casing substantially all the way to the knob 4, against which it may even abut, if desired. The whole length of the shaft outside the casing is thus covered and access to it prevented, as stated in the foregoing 10 part of this description; and this feature is what makes the turning of the shaft impossible by any one boring through the door beside the casing and trying to engage the shaft from the inside in some way other than by getting hold of the knob and manipulating it.

In order to enable the lock 19, which may be a cylinder or other tumbler lock, to actuate the mechanism of our lock we perforate 20 the side of the casing opposite the bearing 3, and mount loosely in the aperture so made a bushing or nipple 23, having an oblong opening 24; and studs 25 on its inner face. These studs will engage similar studs 25 on the face of the cam 12. A tongue 26 which is part of the lock 19 will project therefrom through the opening 24 into the round bore 18. When the knob 4 is turned the shaft can revolve to operate the frames 30 without engaging the tongue 26 or nipple 24; whether our lock is to be fastened or opened. But when our lock is to be operated by a key, the latter will cause the tongue 26 to turn the nipple and the studs 25 thereon 35 to engage with the studs 25 on the cam 12 to actuate the projection 13.

The carrier acts as a means for movably mounting the bolt, and the two cams 8 and 12 may be regarded as a single or unitary 40 means comprising the cams for effecting the desired translational movement of the bolt 6. It will also be appreciated that the flat face on the knob 4 should preferably begin at the shaft 2 and extend outward therefrom, and that there should be no central boss on the knob to receive the shaft; if access to the shaft between the casing and the knob is to be prevented in the most efficient manner. Generally 45 speaking the result desired may be obtained by any form of knob which has its portions most remote from the shaft radially thereof, spaced from the casing substantially no farther than the outer end of the bearing 3, though such portions may extend closer to the casing than the outer end of the bearing if desired. Further, it will be noted that the bolt 6 always extends beyond the front end of the carrier. This structural 55 relation is preferable and makes the lock simpler to construct and operate; though it is only necessary that the bolt project past the forward edge of the carrier when the latter has moved the catch through the opening 14. The frame 6 will always lie

flat against the carrier and if necessary suitable spacing lugs will be placed on the inside of the casing to hold it in this position.

Having described our invention, what we claim 70 as new and desire to secure and protect by Letters Patent of the United States is:

1. The combination of a carrier, a latch bolt movably mounted thereon, and means 75 for moving the carrier and latch bolt in unison, and for subsequently moving the latch bolt with respect to the carrier into engaging position, the bolt in such position projecting beyond the front end of the carrier. 80

2. The combination of a carrier, a latch bolt movably mounted thereon, and means for moving the carrier and latch bolt in unison, and for subsequently moving the latch bolt with respect to the carrier into engaging 85 position, the bolt in such position projecting beyond the front end of the carrier, said means preventing the return of the latch bolt from such position except by the instrumentality of said means. 90

3. The combination of a carrier, a latch bolt movably mounted thereon, means for moving the carrier with the latch bolt and for preventing the return of the carrier except by the instrumentality of said means, 95 and additional means for moving the bolt with respect to the carrier into engaging position.

4. The combination of a carrier, a latch bolt movably mounted thereon, and means 100 for moving the bolt and carrier in unison, and the bolt with respect to the carrier, the bolt then projecting beyond the front end of the carrier, said means acting to prevent reverse movement of the bolt with respect to the carrier, and reverse movement of the carrier and bolt together, except by the instrumentality of said means. 105

5. The combination of a frame having a central opening and a locking projection, a second frame having a central opening and serving as a carrier for the first frame, a shaft and a pair of spaced-apart cams thereon, one of which engages the frame serving as the carrier, and the other of which subsequently 110 engages the other frame bearing the projection, for the purpose set forth. 115

6. The combination of a locking mechanism, a shaft for operating the same and extending therefrom, a knob rigid with the shaft and spaced from said mechanism, and means extending from said mechanism substantially up to the knob for protecting and preventing access to the shaft between the knob and the mechanism, said knob being 120 shaped so that portions thereof radially most remote from the shaft are located at substantially no greater distance from the mechanism than the end of said means adjacent said knob, whereby the shaft cannot be 125 130

rotated except by means of the knob, or by engaging the shaft at some portion other than that protected by said means.

7. The combination of a frame having a central opening and a locking projection, a second frame having a central opening and serving as a carrier for the first frame, a shaft and a pair of spaced-apart cams thereon, one of which engages the inside of the frame serving as the carrier, and the other of which subsequently engages the inside of the other frame bearing the projection, both to actuate said frames and to prevent the return thereof except by the reverse movement of said cams.

8. The combination of an element having a locking projection, a carrier for said element, means for actuating the carrier to move the carrier and the element in unison, means for subsequently giving translational movement to the element, and means for operating both of said means.

9. The combination of a locking mechanism, a shaft for operating the same, a knob on the shaft presenting a substantially

flat face to said mechanism, said face extending from the shaft outward and constituting substantially the whole surface of the knob on the side toward said mechanism, and a fixed bearing extending from 30 said mechanism substantially up to said face for covering and protecting the shaft and preventing access thereto between the knob and said mechanism.

10. The combination of an element having 35 a locking projection, means for movably mounting said element, revolute means for impelling said element translationally in one direction, revolute means for impelling said element translationally in another direction, 40 and means for operating said revolute means forward and reversely to move said element into locking position and to withdraw the same.

Signed at New York in the county of New 45 York and State of New York this 26th day of January A. D. 1916.

BENJAMIN J. COHON.
LOUIS MOSKOWITZ.
